UNITED STATES PATENT OFFICE.

JOHN J. COOK, OF MEDFORD, MASSACHUSETTS, ASSIGNOR TO CROSBY STEAM GAGE & VALVE COMPANY, OF BOSTON, MASSACHUSETTS, A CORPORATION.

SAFETY-VALVE.

1,101,121.

Specification of Letters Patent. Patented June 23, 1914.

Application filed June 13, 1913. Serial No. 773,460.

To all whom it may concern:

Be it known that I, JOHN J. COOK, a citizen of the United States, and a resident of Medford, in the county of Middlesex and 5 State of Massachusetts, have invented certain new and useful Improvements in Safety-Valves, of which the following is a specification.

This invention relates to steam safety valves and more particularly to the form and disposition of the disk employed therein, which is an improvement on that shown and described in Letters Patent Nos. 793,947 and 794,034 dated July 4, 1905. The disk 15 of the patents referred to comprises the middle frustum of a sphere in circumferential engagement with its inclosing cylinder, or cage, and is held to its seat, or seats, by a pintle engaging its center at practically a 20 point, by which pivotal arrangement the disk is enabled to rotate with a minimum of friction, but with the result that, when steam is slowly generating beneath the disk, the latter is liable to flutter and sing, or 25 chatter, thereby causing disagreeable noises. To overcome this difficulty, while preserving the spherical form of disk, is the object of the present invention, which is illustrated by the accompanying drawings in which:

30 Figure 1 is a vertical central section partly in elevation of the safety valve. Fig. 2 is a section on the line 2—2 Fig. 1.

1 is a valve furnished with the base 2, in which is disposed the pop chamber 3 with 35 its outlets 4 controlled by the ring 5 constituting the lower end of the outer casing 5^a, which is in threaded engagement with the valve casing 6 threaded to said base 2. In this base 2 are disposed also the annular 40 valve seats 7 and 8, whereon is seated the valve proper, or disk, 9 which constitutes the middle frustum of a sphere, definable in this instance as including the adjacent parts of two hemispheres. This disk 9 is ar- 45 ranged in the valve casing 6, engaging said casing circumferentially, and is adapted to rise and fall and to freely rotate in any direc- 50 tion, while maintaining said engagement. This disk is furnished on its upper face with the centrally disposed boss 9^a, the top of 55 which forms the zone of a sphere 9^b, concentric with the center of the disk as indicated at 10. The spring washer 11, furnished with the stem 11^a which extends upwardly into and slidably engages the adjustable

spring compression bolt 12 screwed into the valve casing 6, comprises a spider, whose arms 13 slidably engage the valve casing 6 and whose under side is concaved to engage the spherical boss 9^a, forming therewith a 60 ball and socket joint. The spring 14 is mounted in the valve casing being confined between the compression bolt 12 and the spring washer 11.

It is obvious from the construction shown 65 that, whatever position, within the range of its movements, the disk may assume, the sliding contact between the spring washer and the disk, while varying in extent, will never become pivotal and it has been found 70 by experiment that this sliding contact affords enough friction to prevent the fluttering of the disk which, as has been said, may occur when the pivotal arrangement of disk and pintle is employed as in the earlier 75 patents.

I claim:

1. In a safety valve, the combination, with the valve base, valve casing mounted thereon and valve seat disposed therein, of 80 a disk constituting the middle frustum of a sphere, circumferentially engaging said casing and furnished on its upper face with a boss terminating in the frustum of a sphere concentric with that of the disk; a concaved 85 spring washer engaging the boss of the disk and forming therewith a ball and socket joint; and a spring surmounting the spring washer.

2. In a safety valve of the character de- 90 scribed, in combination, a disk constituting the middle frustum of a sphere and furnished on its upper face with a boss terminating in the frustum of a sphere concentric with that of the disk, and a concaved 95 spring washer forming with said boss a ball and socket joint.

3. In a safety valve, the combination, with the valve base, valve casing mounted thereon and valve seat disposed therein, of 100 a disk constituting the middle frustum of a sphere, circumferentially engaging said casing and furnished on its upper face with a boss terminating in the frustum of a sphere concentric with that of the disk; a 105 concaved spring washer slidably engaging the valve casing and forming with said boss a ball and socket joint; and a spring surmounting the spring washer.

4. In a safety valve of the character de- 110

scribed, in combination, a disk constituting the middle frustum of a sphere and furnished on its upper face with a boss terminating in the frustum of a sphere concentric with that of the disk; and a concaved spring washer slidingly engaging the valve casing and forming with said boss a ball and socket joint.

5. In a safety valve of the character described, in combination, a disk constituting the middle frustum of a sphere and furnished on its upper face with a spherical boss concentric with said disk; and a con-

caved spring washer forming with said boss a ball and socket joint.

6. In a safety valve of the character described, a disk constituting the middle frustum of a sphere and furnished on its upper face with a spherical boss concentric with said disk.

15 In testimony whereof I have affixed my signature, in presence of two witnesses.

JOHN J. COOK.

Witnesses:
